UNITED STATES PATENT OFFICE.

HENRY YEOMAN EVANS, OF EGHAM, ENGLAND.

DOOR AND LOCKING DEVICE THEREFOR.

Application filed June 12, 1923. Serial No. 644,999.

To all whom it may concern:

Be it known that I, HENRY YEOMAN EVANS, a subject of the King of Great Britain, and resident of Egham, in the county of Surrey, England, have invented certain new and useful Improvements in Doors and Locking Devices Therefor, of which the following is a specification.

This invention relates to doors and locking devices therefor and more particularly to the construction of the doors of rotary drums or cages of washing, drying, cleaning machines and the like but the improvements hereinafter described are equally applicable to other purposes such as doors of theaters and other places of public entertainment provided with what are known as "panic" bolts.

The main object of the present invention is to provide an improved construction of door that can be readily applied to such rotary drums aforesaid for example, and locking devices therefor by the operation of which the door is securely clamped in the closed position. A further object is to provide means whereby should the machine be started and the drum revolved in either direction with the door unlocked, the said door is automatically locked and a still further object is to provide a door carried on rollers so arranged that the door is not apt to run back on to and thereby injure the hands of the operator of the machine.

Further objects and advantages of the invention will be apparent from the detailed following description thereof with reference to the accompanying drawings, the novel features being pointed out in the appended claims.

In the said drawings wherein similar reference characters relate to like parts in all the figures:—

Figure 1 is a cross section of a rotary drum having a slidable door and locking devices thereon constructed according to this invention, the door being shown in the open position.

Figure 2 is a plan view looking in the direction of the arrow to show the guide frame, the door and door frame, the locking means and cooperating parts.

Figures 3, 4, 5 and 6 are detail views to a larger scale.

Figure 3 showing a portion of the guide frame, the locking cam in its closed position

and the recess in the frame in which the cam engages.

Figures 4 and 5 are plan and sectional elevation respectively of the locking mechanism and.

Figure 6 is a sectional view to show one of the door rollers.

In the application of the invention shown in the drawings *a* represents a guide frame that may be secured by means of bolts or rivets to the shell of the rotary drum *b* in which is provided the door opening *c* adapted to be closed or exposed by the slidable door *d* that is curved to conform to the peripheral surface of the drum *b* and is provided with front and rear rollers *e* and *f* carried by the spindles *g* mounted in the bosses *g'* formed on the longitudinal angle bars *h* of the door frame *h* that is fixedly mounted on the door *d*. Along the upper edge of the door opening *c* is disposed the angle iron *k* fixed to the inner surface of the shell *b* and along the lower edge of the said opening is disposed the Z-iron *k'* the horizontal flange of which is fixed to the outer surface of the shell *b*. The front edge *d'* of the door *d* is bent slightly upwards as shown in Figure 1 in order that in the closed position it may rest on the horizontal flange of the Z-iron *k'*, the members *k* and *k'* forming sealing members on which the top and bottom edges of the door are clamped when pressure is applied to lock the door as herein-after described. Recesses *l* *l'* are formed in the guide frame *a* to receive the rollers *e* and *f* in the closed position of the door *d* and so that the rollers *f* shall not fall into the recesses *l* when the door is being opened the rollers *e* and *f* are placed in different circumferential planes so that they travel on opposite sides of the central webs of the guide frame *a*, the rollers *e* travelling on the flanges *i* and the rollers *f* on the flanges *j*.

The locking cams *m* are of the shape shown in Figure 3 with long and short diameters and they are formed on the ends of the spindle *n* rotatably mounted in the bars *h'* and operated by means of the levers *o*. In the closed position of the door by rotation of the spindle *n* the cams *m* are turned into such a position that the edges *m'* of the cams *m* engage the top of the apertures *p* in the guide frame *a* and thereby press the door *d* inwardly against the horizontal sealing members *k* *k'* effectively locking it in the

closed position. To unlock the door the spindle n is rotated by the levers o whereby the cams m are turned into the position shown in Figures 4 and 5 with their long 5 diameters disposed across the apertures p and the pressure on the door d is relaxed and it can be moved into the open position running freely on its rollers e and f .

To maintain the cams m in either the 10 closed or open positions the construction shown in Figures 4 and 5 is employed.

q is a helical spring disposed around the spindle n one end of the said spring abutting against the lever o and the other end against a collar r having a sliding movement on the spindle n due to the pin t of the collar r engaging in the slot s . The outer face of the collar r is provided with projections u which engage with corresponding 15 projections v on a second collar w having a rigid connection to the bar h . It will be obvious that when the lever o is operated to rotate the spindle n either to apply or release the locking cams m the collar r is disengaged from the collar w but on release of the lever o the collars r and w immediately 20 reengage and the cams m are locked in their open or closed positions as the case may be.

It will be obvious that in the closed position the door will be kept rigid by the operation of the locking cams m and if, inadvertently the machine is caused to rotate with the door unlocked that the door must automatically be locked in whichever direction the movement takes place by the lever o striking against the edge of the outer shell of the machine.

In arranging the position of the rollers e and f which carry the door d I place them 30 so that when the door is opened upwards the centre of gravity is beyond the vertical line, so that the door is not apt to run back on the hands of the operator of the machine.

What I claim is:—

45 1. In combination, a door, rollers carried by said door, a guide frame forming a path for said rollers and provided with depressions in which said rollers engage in the closed position of the door, a pair of sealing members, and means for moving said door against said sealing members and for causing the rollers to enter the depressions in 50 said guide frame.

2. In combination, a rotary drum with an opening in the shell thereof, a door for closing and exposing said openings, rollers carried on a door frame fixedly mounted on said door, a guide frame forming paths for said rollers and provided with depressions in different circumferential planes of said drum, said rollers engaging in said depressions in the closed position of the door, a pair of sealing members on said drum, cams formed on a spindle rotatably mounted in said door frame and slidable through said guide frame and means for rotating said spindle to cause said cams to press said door against said sealing members and to force the rollers into said depressions. 55

3. In combination, a rotary drum with an opening in the shell thereof, a door for closing and exposing said opening, rollers carried on a door frame fixedly mounted on said door, a guide frame forming paths for said rollers and provided with depressions in different circumferential planes of said drum, said rollers engaging in said depressions in the closed position of the door, a pair of sealing members, cams formed on a spindle rotatably mounted in said door frame, and levers for rotating said spindle to cause said cams to engage the upper ends of openings in said guide frame to press said door against said sealing members and to force the rollers into said depressions. 75

4. In combination, a rotary drum with an opening in the shell thereof, a door for closing and exposing said opening, rollers carried on a door frame fixedly mounted on said door, a guide frame forming paths for said rollers and provided with depressions in different circumferential planes of said drum, said rollers engaging in said depressions in the closed position of the door, a pair of sealing members, cams formed on a spindle rotatably mounted in said door frame, levers for rotating said spindle to move said cams whereby to press the door against said sealing members and to force the rollers into said depressions, said cams 90 adapted to be turned sidewise and to slide longitudinally of said guide frame when the door is moved to open and closed positions. 95

In testimony whereof I affix my signature.

HENRY YEOMAN EVANS.
